UNITED STATES PATENT OFFICE.

ALFRED E. KING, OF ST. KILDA, NEAR MELBOURNE, VICTORIA, AUSTRALIA.

COPY HOLDER FOR USE WITH TYPEWRITERS.

1,405,040.

Specification of Letters Patent. Patented Jan. 31, 1922.

Application filed September 8, 1919. Serial No. 322,505.

To all whom it may concern:

Be it known that ALFRED ERNEST KING, a subject of the King of Great Britain, residing at 191 Fitzroy Street, St. Kilda, near

5 Melbourne, in the State of Victoria, Australia, has invented certain new and useful Improvements in Copy Holders for use with Typewriters, of which the following is a specification.

10 In connection with typewriting machines several devices have been proposed for holding the copy but as they have not been generally adopted may be regarded as more or less inefficient. Some forms of such devices 15 are large and cumbersome and are mounted at the back of the machine at too great a distance for clear vision of the copy while other devices have been used at the side of the machine necessitating constant turning 20 of the head.

According to this invention the copy is arranged to be adjustably held in the same or approximately the same focal plane as the work of the machine. In a preferred practical form the copy holder is arranged to expose a portion of the transcript and progressively feed same, and is also adjustable for location in the same or approximately the same focal plane as the work of the machine to suit the operator and light.

Generally the invention may be practically applied by an adjustable copy-holder comprising a frame or casing with means for gripping the copy and controllable means for feeding the latter upwardly with only a portion of the copy matter exposed, means for guiding the copy away from the machine and adjustable supporting means for varying the distance, height and angularity of the casing whereby it may be positioned in approximately the same focal plane as the line of work and in close proximity to the latter.

The device may be mounted on a standard 45 fixed to the table upon which the machine is placed or to the machine frame or to the wall or any convenient stationary object in proximity to the machine.

The invention as applied in a practical form is depicted by the accompanying drawings.

Fig. 1 is a front elevation of the copy holder showing the hinged paper guide swung down, some parts being broken to better illustrate the construction.

Fig. 2 is a plan (broken) showing the copy holder open to receive the copy.

Fig. 3 a side elevation (broken).

Fig. 4 an enlarged vertical section on line IV Fig. 1.

Fig. 5 an enlarged view of part of Fig. 3 partly in section.

Fig. 6 an outline plan of a typewriter showing the copy holder located approximately in the same focal plane as the line of work and mounted on a standard fixed to a corner of the typewriter frame.

The copy holder according to the drawings comprises a frame 1 braced by transverse rods 2, 3, 4 and provided with a hinged 70 elongated face plate 5 fixed to a light frame 20 and having an aperture 50 through which a portion of the copy C is visible.

The area or depth of this aperture is regulated by a slide shutter 7 engaging end 75 guides 8 and provided at the rear near its ends with racks 9 engaging pinions 10 on a rod 11 journaled in the frame 20 one end of said rod being extended through said frame and provided with a milled finger disc 80 12. By means of this construction one or more lines of the copy are visible at a time and the bottom edge of the aperture acts as a line guide.

In order to indicate the stop work position 85 on the copy a horizontally slidable pointer 51 is mounted in a slot 13 formed in the front plate 5 of the holder. The front plate is pivoted to swing open on the frame of the holder to permit insertion of the copy C. 90 As illustrated the plate 5 is hinged at one end to the frame 1 on pivot 74 to swing outwardly, but it may be hinged instead at the top or bottom and any suitable catch device is employed to keep the plate closed such as 95 a spring catch 14 adapted to engage a hook 15 on the frame. Links 52, 53 pivoted respectively to the bar 2 and the frame 20 are provided to limit the swing of the face plate. Journaled in the end pieces of the 100 frame 20 of the face plate are two freely rotatable rollers 16, 16 provided with interrupted gripping surfaces 17 of rubber or the like. These rollers cause the copy sheet or book C to be pressed against a manually rotatable feed roller 18, having a rubber or like surface and being provided at each end with a milled finger disc 19. The feed roller 18 is capable of yielding by spring means to

105 accommodate copy of varying thicknesses. 110

For this purpose the spindle 21 of the roller 18 is provided at each end with a collar 22 engaged between the limbs 23 of a bifurcate arm 24 mounted on the transverse rod 4, said 5 arm being spring actuated to press the feed roller towards the rollers 16. As illustrated each arm 24 has rigidly fixed to it a cylinder 25 containing a spring 26, one end being connected to the bar 4 and the other to the 10 cylinder or attached arm.

Each collar 22 is made integral with a slide block 27 formed with guide flanges and adapted to slide between guides 28 provided on the frame 1. The frame 1 is provided 15 at the rear about the bottom with a guide shield 29 to guide the lower part of the copy sheet and prevent same contacting with any part of the typewriter or obscuring the matter typed. As illustrated the 20 shield 29 is hinged on the transverse bar 3 and may consist for lightness of a frame 30 with spaced thin strips of metal 31. Above the feed roller 18 is a copy paper guide of sheet metal 32 preferably secured to the arms 25 24 for leading away the upper portion of the copy.

The copy holder is pivoted to turn in an upward or downward direction upon frame member 1 and for this purpose the bar 4 is rotatably mounted in bearings formed in 30 two plates constituting a bracket 33, the plates being drawn towards each other by screws 34 to grip said bar 4 somewhat tightly in the bearings so that the frame 35 will remain at the desired inclination. The bracket 33 is connected by a pivot 35 to one member 36 of a horizontally projecting bracket or jointed arm, said member 36 being connected by a pivot 37 to a similar 40 member 38 mounted at its other end upon a pivot 39 provided on any conveniently situated vertically adjustable rigid bracket 40.

As illustrated in Figs. 1, 2, and 3 the bracket 40 projects from a standard 41 of 45 circular cross section telescopically and rotatably fitting a hollow pedestal 42 formed with a base 43 for attachment to a table or floor upon which the typewriter is placed. To permit vertical adjustment of the standard 50 it is provided with a laterally projecting clamping screw 44 adapted when loosened to slide up or down a vertical slot 45 and be turned at right angles to engage one or other of a series of bayonet slots 46 55 offset from said slot 45, said screw being tightened when the copy holder is raised to the desired elevation. It will be evident that a rigid standard might be used and the bracket 40 arranged to slide vertically in 60 guides thereon in lieu of the telescopic construction just described. Furthermore it may be more convenient to have the bracket 40 vertically adjustable on a wall or other fixture or movable element located conveniently 65 to the typewriter.

In Figure 6 the pedestal 42 supporting the standard 41 is curved at the lower end 47 with its base fitting one corner of the typewriter frame 48 and secured by a screwed down plate 49 on said frame. By 70 means of the mounting of the copy-holder frame described it will be evident that said holder may be regulated as regards elevation and swung horizontally on the supporting members 36, 38 to a position suitably 75 distant to the typist and turned horizontally on pivot 35 at a convenient angle if desired to obtain full advantage of the light, while furthermore for the same object the copy-holder may be tilted if desired by partially 80 rotating the bar 4 in the bearings of the bracket 33.

It will be evident that by using readily detachable pivots such as bolts and nuts at the joints of the supporting means, the latter may be readily dismantled and the whole device packed in a comparatively small compass while furthermore by detaching pivotal bolt 39 the copy-holder can be readily removed.

Fig. 6 shows the copy-holder in approximately the same focal plane as the line of work and also in close proximity to the latter, which for the majority of typists would be the most convenient position as it 95 would obviate unnecessary repetitions of a turning movement of the head as is usual where the copy is not located in the position described.

In order to insert the copy, the hinged 100 face plate 5 is opened and the copy placed against the feed roller 18 with the lower portion above the guide shield 29 set as desired. The face plate 5 is then closed when the copy is gripped between rollers 105 16, 16 and 18 and fed forward as required by turning knob 19, the shutter 6 controlling the view aperture 50 being regulated as desired to expose one or more lines of the copy.

It will be evident that by reason of the spring controlled arms 24, the feed roller is yieldingly held against the rollers 16, 16 and is capable of being pressed backwards to permit comparatively thick note or copy books to be gripped between the rollers 16, 110 16 and 18.

I claim—

1. A copyholder for use with typewriters, 115 adjustably mounted for location in the use or approximately the same focal plane as the work of the machine and formed with a frontal aperture the area of which is regulated by a guided slide shutter operated by manually rotated pinions gearing with racks 120 on said shutter.

2. A copyholder for use with typewriters, 125 adjustably mounted for location in the same or approximately the same focal plane as the work of the machine and formed with a 130

frontal aperture the rear of which is regulated by a guided slide shutter operated by manually rotated pinions gearing with racks on said shutter and means for progressively feeding said transcript past said aperture.

5. A copyholder for use with typewriters, adjustably mounted for location in the same or approximately the same focal plane as the work of the machine, said holder being 10 formed with a front apertured face plate hinged to open for insertion of the transcript and provided with gripping rollers on its rear cooperating with a feed roller and a hinged shield to guide the lower portion of the 15 transcript.

4. A copyholder for use with typewriters, adjustably mounted for location in the same or approximately the same focal plane as the work of the machine, said holder being 20 formed with a front apertured face plate hinged to open for insertion of the transcript and provided with gripping rollers on its rear co-operating with a feed roller and a guide for the upper portion of same.

25. 5. A copyholder for use with typewriters, adjustably mounted for location in the same

or approximately the same focal plane as the work of the machine, said holder being formed with a front apertured face plate 30 hinged to open for insertion of the transcript, a spring controlled adjustable feed roller co-operating with rollers on said plate, the spindle of said roller being fixed to guided slides and formed with collars engaged by the bifurcated ends of spring controlled arms pivoted on the frame of the holder.

6. A copyholder for use with typewriters, adjustably mounted for location in the same or approximately the same focal plane as 40 the work of the machine, said holder being formed with a front apertured face plate hinged to open for insertion of the transcript, a spring controlled adjustable feed roller co-operating with rollers on said 45 plate, the spindle of said rollers being fixed to guided slides and formed with collars engaged by the bifurcated ends of spring controlled arms pivoted on the frame of the holder and a transcript guide attached to 50 said arms.

ALF. E. KING.
